KNOCKDOWN PICNIC TABLE AND
BENCH ASSEMBLY

John P. Lysaght, Milwaukee, Wis.

Application October 17, 1952, Serial No. 315,267

5 Claims. (Cl. 155—124)

1

This invention relates to picnic and camping equipment and more particularly to a knockdown picnic table and bench assembly which can be easily disassembled, folded and transported in the trunk of an automobile.

One of the prime objects of my invention is to design a picnic table and bench assembly, the component sub-assembled parts of which can be compactly folded for storage and/or transportation in areas of small compass such as the trunk of an automobile, so that they can be transported to a desirable location and assembled for use with a minimum of time and effort, and later disassembled and folded for return in the vehicle.

Another object of my invention is to design a knockdown table and bench assembly which can be very rapidly set up and/or disassembled without the use of tools of any kind.

A further object of my invention is to design a table and bench assembly of the type described, which is neat and pleasing in appearance, and of simple and durable construction, and which can be very economically manufactured.

A still further object of my invention is to design a knockdown table and bench structure which can be disassembled into a very few sub-assembled parts, each sub-assembly being of sufficient size so that the possibility of loss or misplacement is eliminated, and which requires no bolts or screws to assemble.

With the above and other objects in view, the present invention consists in the combination and arrangement of parts, hereinafter more fully described, illustrated in the accompanying drawings, and more particularly pointed out in the appended claims, it being understood that changes may be made in the form, size, proportion, and minor details of construction, without departing from the spirit, or sacrificing any of the advantages of the invention.

In the drawings:

Fig. 1 is a perspective plan view of my knockdown picnic table and bench assembly set up for use, the table top being shown as comprised of two hingedly connected folding sections.

Fig. 2 is a side elevational view thereof.

Fig. 3 is an inverted plan view of the sub-assemblies, the table top being shown as unitary.

Referring now more particularly to the accompanying drawings in which I have shown the preferred embodiment of my invention, the table and bench assembly includes a pair of folding benches B which comprise tops or seats 10 with leg sections L hingedly connected thereto by means of hinges 12 to fold inwardly towards each

2 other as illustrated in Fig. 3 of the drawings.

The leg sections L comprise legs 13 joined by cross braces 14 and 15, and it will be noted that pairs of spaced-apart strips 16 are provided on the upper face of the braces 15 and 16 and that braces 17 span the pairs of legs 13 with the ends accommodated between said strips 16 when the bench is set up, triangular braces 18 being secured to the lower face of the braces 17 adjacent the ends thereof to abut the cross braces 15 and maintain the leg sections L in spaced-apart relation.

To conveniently maintain the leg sections L in folded position when desired, centrally disposed blocks 19 are secured to the lower faces of the tops 10, and dutchmen 20 are provided thereon, and can be rotated to overlie the braces 15, all as shown in Fig. 3 of the drawings.

Open ended, transversely disposed housings 21 depend from the ends of the bench tops 10 adjacent the leg sections L to receive the ends of a pair of bench connecting support members 22. The housings 21 also serve to prevent the leg sections L from swinging outwardly past a vertical position when the benches B are occupied.

Pivotedly connected to the supports 22 interjacent the ends thereof by means of pins P are pairs of uprights or legs 23. The uprights 23 are so positioned that a table top 24 supported thereon will be equidistant from the benches B. Depending flanges 25 are formed on the table top 24 which is of a size to snugly receive the upper ends of the uprights 23 in the corners thereof when the latter are in vertical position.

The uprights 23 are prevented from swinging inwardly past vertical position by a brace 26 provided on the side of the support member 22, and it will be obvious that when the table top 24 is also mounted on the ends of the uprights 23, that the legs are prevented from swinging outwardly by the flanges 25 and firmly support the top 24 in position.

In Fig. 1, the top is shown as composed of a pair of hingedly connected sections which are foldable, but it is to be understood that this form is optional and that the unitary top depicted in Fig. 3 can also be employed in practicing the invention. I find it quite convenient to use the foldable top when a knockdown serving table of suitable design is adjunctively employed in conjunction with my table and bench assembly, the component parts of the serving table fitting nicely within the folded top 24 which can be provided with a latch and a carrying handle (not shown) for convenient handling.

To reduce the assembled structure shown in

55

Fig. 1 to the knocked down condition depicted in Fig. 3 so that the various parts may be conveniently stored and transported, it is merely necessary to lift the top 24 off the uprights 23, move the benches B outwardly until the ends of the supports 22 are free of the housings 21, and then swing the uprights 23 down to lie flush with the supports 22. Thence the braces 17 are removed from between the bench leg sections L and the leg sections L are folded inwardly and latched by the dutchman 21. The assembly is, of course, effected in the same manner without the use of tools and with a minimum of effort. It will be obvious that the various knocked down parts shown in Fig. 3 can be stored in a relatively small place, out of the way, and yet are ready for instant assembly when necessary.

From all of the foregoing, it will be obvious that I have perfected a very simple, practical and inexpensive knockdown table and benches, which can be easily and quickly assembled and disassembled, and which can be stored in a very small area, or transported in the trunk of an automobile for use when desired.

What I claim is:

1. In a knockdown table and bench assembly, a pair of spaced-apart, parallelly disposed benches having seats and hingedly connected leg members, means on the ends of said benches for removably receiving and supporting a pair of bench-connecting support members, uprights pivotally connected to said support members, a table top having depending rims on the upper ends of said uprights, and means for preventing said uprights from swinging inwardly past vertical position.

2. The combination defined in claim 1 in which said means comprises horizontally disposed spacer members mounted on said support members between said uprights.

3. The combination defined in claim 1 in which each leg section comprises a pair of legs and a cross brace spanning and connecting said legs, centrally spaced-apart transversely disposed blocks on said cross braces and removable braces of sufficient length to be accommodated between said blocks adapted to span said leg sections when said benches are set up, said braces having depending abutments adjacent the ends thereof to engage said cross braces and maintain said leg sections in spaced-apart position.

4. In a knockdown table and bench assembly, a pair of spaced-apart, parallel benches having seats and leg sections hingedly connected to the underside of said seats at spaced distances from the ends thereof, transversely disposed, open-ended housings depending from said seats adjacent the outer faces of said leg sections when the leg sections are in vertical position, a pair of horizontally disposed bench-connecting support members removably received in said housings, pairs of uprights pivotally mounted on said support members intermediate said benches and swingable from a folded position with respect to said support members to a vertical upright position, spacer members on said support members between each pair of uprights to prevent said uprights from swinging inwardly past vertical position, and a table top having depending rims snugly accommodating the upper ends of said uprights in the corners thereof to rigidly support and stabilize said table and prevent outward swinging movement of said uprights.

5. In a knockdown table and bench assembly, a pair of spaced-apart, parallelly disposed benches having seats and hingedly connected leg members, transversely disposed, open ended housings depending from the ends of the seats of said benches for removably receiving and supporting a pair of bench-connecting support members, uprights pivotally connected to said support members, a table top having depending rims on the upper ends of said uprights, and means for preventing said uprights from swinging inwardly past vertical position.

JOHN P. LYSAGHT.
